FIGURE 1 is a front elevational view of a photographic camera or similar article, showing our new design;

FIG. 2 is a side elevational view thereof;

FIG. 3 is a rear elevational view thereof;

FIG. 4 is an elevational view thereof taken from the opposite side from that shown in FIG. 2;

FIG. 5 is a front elevational view thereof, showing the parts thereof in open position;

FIG. 6 is a side elevational view thereof, shown in open position;

FIG. 7 is a top view thereof, shown in open position;

FIG. 8 is a bottom view thereof, shown in open position; and

FIG. 9 is an elevational view thereof, shown in open position and taken from the opposite side from that shown in FIG. 6.

We claim:

The ornamental design for a photographic camera or similar article, substantially as shown.
